ELECTRIC CIRCUIT

Hans Koch, Magdeburg-Buckau, Germany

Application February 24, 1932, Serial No. 594,869

2 Claims. (Cl. 179—1)

This invention relates to the distant control of electric circuits by primary and secondary circuits, it being immaterial how far the switching elements are remote from the arrangement 5 to be controlled evidently connected therewith by wires. The fundamental novelty of the invention is based on the fact that an impulse sent by a secondary circuit, that is the momentary closing of a secondary circuit, switches out and 10 renders currentless the primary circuit and is only placed under current at the moment of switching.

In the drawing an embodiment of the invention suitable for wireless receiving is illustrated 15 diagrammatically in the only figure of the accompanying drawing.

A wire 19a, 19b extends from the terminal 1 to a switching in switch E from which a further wire 19a, 19d leads to one pole of a relay 20 20 the other pole of which is connected to the terminal 2 by means of a wire 19e. Thus the battery 18 is connected up in a circuit with the switching in switch E and the relay 20, so that if the switch E is actuated this circuit is closed 25 and the relay 20 energized.

On the relay 20 four blade springs 36, 37, 38, 39 are fixed mutually insulated at one end, the springs 36 and 38 having near their other end contacts 40 and 41 respectively.

30 A two-armed lever 33, 34 is oscillatably mounted on the relay 20 and its arm 34 carries an insulated pin 35 extending freely through apertures in the blade springs 36 and 37 and consequently insulated therefrom.

35 When the relay 20 is excited the arm 33 of this two-armed lever is attracted causing its arm 34 to swing upwards so that the end of this arm presses the spring blade 36 upwards bringing its contact 40 against the blade spring 37 whereas 40 the pin 35 lifts the blade spring 38 away from the spring 37 so that the spring 37 cannot contact with the spring 38 and at the same time presses the contact 41 against the spring 39.

The blade spring 39 is, however, connected by 45 a wire 19k to the terminal 4 connected to the receiving set by a wire 15 and the blade spring 38 is connected by a wire 19s to the other terminal 3 connected to the receiving set by the wire 14 so that when the contact 41 is closed the circuit of the receiving set is closed.

50 The wire 19c is also connected to the blade spring 36 by wires 19i and 19h, whereas the contact spring 37 is connected to the terminal 1 of the battery by a wire 19g a normally closed blade spring contact 29, 31, 30 and a wire 19f, so that

when the switching in press-button E is released and the wires 19b and 19c become currentless, the relay 20 still receives current through 19f, 30, 31, 29, 19g, 37, 40, 36, 19h, 19i, 19d and remains excited and keeps the receiving set circuit closed. 5

The wire 19i is extended by a wire m to the terminal 5 and the terminal 6 is connected by a wire 19r with the wire 19f leading to the terminal 1 of the battery. A further switching in press button switch in a further extension connection may be connected up with the terminals 5, 6 by wires 10 and 11. If this press button switch is depressed the relay 20 will also be excited by current supplied thereto through 19f, 19r, 6, 11, the further extension press button 10 switch not shown, 10, 5, 19m, 19i, 19d and when this further extension press button is released the relay will also remain under current as 15 above described.

The above mentioned blade springs 29 and 30 20 are also mounted mutually insulated on a second relay 22, together with a third spring 32 which is dead and only intended for emergency use. As above stated a contact 31 on the blade spring 29 normally bears against the spring 30. 25

A second circuit 21 is connected with the terminals 1 and 2 of the battery 18. This second circuit is a switching out circuit comprising a wire 21a leading from the terminal 2 to a switching out press-button switch A whence wires 21b, 30 21c lead to one pole of the second relay 22, the other pole of the relay 22 being connected to terminal 1 by a wire 21d. Thus if the switch A is actuated the relay 22 will be excited. A two-armed lever 23, 25 is oscillatably mounted about 35 a support 27 on the relay 22 so that when the relay is excited the arm 23 of this lever will be attracted causing the arm 25 to swing upwards. A pin 28 is mounted on the arm 25 and extends with clearance through a hole in the blade spring 29 so that when this arm 25 swings upwards the pin 28 will push the spring 30 away from the contact 31 thereby breaking the circuit 19 at this point. Thus the wire 19g becomes currentless and current no longer flows through the springs 37, 36, the wire 19h, 19i, 19d to the relay 20 which consequently ceases to attract the lever 33 with the result that it swings back into its inoperative position breaking the contact 40 and lowering the pin 35 so that the contact 41 is also broken, 40 50 and the receiving set circuit interrupted.

If a further extension connection is provided its switching out press button not shown is connected to the terminals 7 and 8 and the terminal board 9 by wires 12 and 13. The terminal 8 is 55

- connected directly with the terminal 2 of the battery by a wire 21f, whereas the terminal 7 is connected with the wire 21c by a wire 21g. If this further switching out press button is depressed when the relay 20 is under current and the receiving set circuit is closed as above described, current will flow from the battery to the relay 22 along the following path 21f, 8, 13 to the switch, thence over 12, 7, 21g, 21c and 21d. 5
- 10 Thus the relay will be also excited and attract the armature 23, 25 thereby interrupting the current supply to the relay 20 in the manner above described.

It is evident that the switching in and switching out press-buttons of any number of extension connections may be connected up in parallel to the wires 10, 11 and 12, 13 respectively so that if any of these further press-buttons are depressed the relays in the circuits shown will 15 be actuated in the manner above described.

I claim:

1. A remote control for a wireless receiving set, comprising in combination a receiving set circuit 20 battery, a switching in circuit connected up with 25 said battery, a relay connected up in said switching in circuit, a contact device controlled by said relay and connected up in said receiving set circuit, means for momentarily closing said switching in circuit to excite said relay to actuate said 30 contact device and close said receiving set circuit, a second contact device connected with said battery, said switching in circuit and with said relay through the intermediary of said first mentioned contact device to maintain said relay in 35 excited condition, a switching out circuit connected with said battery, a second relay carrying said second contact device and connected up in said switching out circuit, and means for momentarily closing said switching out circuit to 40 excite said second relay to actuate said second contact device and interrupt the current supply

to said first relay and break said receiving set circuit.

2. A remote control for a wireless receiving set, comprising in combination a receiving set circuit, a battery, a switching in current connected with said battery, a relay connected up in said circuit, a press button switching in switch connected up in said circuit and adapted to momentarily close said circuit to excite said relay, four mutually insulated blade springs arranged 10 in pairs on said relay the lower pair of springs having registering apertures and the upper pair connected up in said receiving set circuit, a relay armature in the form of a two-armed lever pivotally mounted on said relay one arm of said armature adapted to be attracted by said relay and the other arm adapted to press against the lowermost of said springs and press same into contact with the next higher spring, a pin insulated on said second arm extending with clearance 15 through the apertures in the lower pair of springs and press together the upper pair of springs to close said receiving set circuit, a retaining circuit connected with said switching in circuit and to said lower pair of springs, a pair of normally 20 closed contact springs in said retaining circuit adapted to maintain said relay under circuit through the intermediary of said lower pair of contact springs after the contacting of said lower springs, a switching out circuit connected with 25 said battery, a second relay in said switching out circuit, a switching out switch in said switching out circuit adapted to close this circuit to excite said second relay, an armature on said second relay adapted to be attracted by said second relay and break the contact between said 30 pair of normally closed contacts to break said maintaining circuit to interrupt said receiving set circuit through the intermediary of said upper 35 pair of contact springs.

HANS KOCH.
